UNITED STATES PATENT OFFICE.

FRANK S. STERNAD, OF AKRON, OHIO, ASSIGNOR TO THE B. F. GOODRICH COMPANY, OF NEW YORK, N. Y., A CORPORATION OF NEW YORK.

SHEET-FEEDING MECHANISM.

Application filed September 24, 1927. Serial No. 221,826.

This invention relates to sheet feeding means suitable, for example, for removing cut strips of fabric from bias cutters, and especially vertical bias cutters of the traveling knife type, such as are used for obliquely cutting a web of fabric into strips for use in the building of pneumatic tires.

When the fabric is heavily rubberized it has frequently happened that the cut strip 10 has so adhered to the residue of the strip after passage of the knife, the cut edges closing together and "healing" behind the knife, that it has been necessary to have workmen stand in readiness to dislodge the cut strips 15 by hand.

The chief objects of my invention are to provide a bias cutter including take-off means adapted automatically, positively and accurately to withdraw the cut strips from the 20 residue of fabric and cause them to pass regularly onto conveyor means adapted to carry them away in regular order.

Of the accompanying drawings:

Fig. 1 is an elevation of a vertical bias 25 cutter embodying my invention in its preferred form.

Fig. 2 is a section on line 2—2 of Fig. 1.

Fig. 3 is a section on line 3—3 of Fig. 1.

Fig. 4 is a section on line 4—4 of Fig. 1.

Fig. 5 is a section on line 5—5 of Fig. 1.

Referring to the drawings, the invention is here shown embodied in a vertical bias cutter 10 which in general is of a construction well known in the art, being provided with the usual presser bar 11, presser-bar guide 12, traveling knife 13 and knife-guiding members 14, 15, and adapted to cut obliquely into bias strips a web of fabric 16.

The machine also comprises a set of inclined endless belts 17, 17 adapted to receive the cut strips and carry them away from the machine, the belts 17 being mounted upon respective sheaves 18, 18 which are journaled upon brackets 19, 19 secured at spaced intervals upon a supporting bar 20 which is secured in a pair of supporting brackets 21, 21 projecting from the machine frame.

My improvements include a presser plate 22 mounted in position for the successive cut strips to overlie its front face as the strips are cut. The plate 22 is mounted parallel with the knife-guiding members 14, 15 and is adapted to slide on the forward face of the member 15, in a direction at right angles to 55 its length and to the path of the knife.

Near each of its ends the plate 22 is provided with an anti-friction roller 23 journaled upon a stud bolt 24 projecting from the rear face of the plate, the roller being mounted to run in a slot 25 formed in a 60 bracket 26 secured to the framing, and the stud bolt being provided at the rear of the bracket with a washer 27 and nut 28.

For moving the plate 22 toward and from the path of the knife in time with the successive cutting operations, the plate at each end is connected by an adjustable link 29 with a lever, 30 or 31, keyed upon a shaft 32 which is journaled in the bar 20, the latter being hollow. The lever 31 has a rearwardly extending arm which is connected by a pull spring 33 with the base of the machine frame to urge the plate 22 toward the path of the knife 13, and for periodically moving the plate 22 in the opposite direction the shaft 32 70 has secured thereon an arm 34 provided with a series of attachment apertures 35, 35 for a cable 36 having connection through a turnbuckle 37 (Figs. 1 and 2) with a cam lever 38 provided with a series of attachment apertures 39, 39, the lever 38 being fulcrumed upon the machine frame at 40 and provided with a cam roller 41 on its rear arm adapted to coact with a cam 42 secured upon a shaft 43 of the machine. Thus the construction 75 is such that the plate 22, with the cut strip of fabric lying against its forward face, will be moved away from the line of cut immediately after each cutting operation, and then returned to a position close to the line of cut to receive the next strip of fabric.

In order to press the fabric strip against the plate 22 and compel it to move downward therewith, a series of plungers 44, 44 are telescoped upon respective guide bars such as the bar 45 (Fig. 4) and each plunger is urged toward an extended position with relation to its guide bar by a compression spring 46 mounted within the plunger and bearing against the outer end of the guide bar 45, the action of the spring being limited by a stud 47 projecting from the guide bar 45 through a slot 48 formed in the wall of the plunger.

The several guide bars 45 are secured in respective clamps 49, 49 slidably keyed upon 105 a shaft 50 and adapted to be secured in spaced apart relation thereon by respective set screws 51, 51.

The shaft 50 is journaled in three journal brackets 52, 52 formed upon respective slides 110

which are held against the lower side of the presser-bar guide 12 by retaining plates such as the plate 53, 53 (Figs. 3 and 5) and are rigidly connected to the presser bar 11, to be moved backward and forward therewith, by means of bars 54, 54 and brackets 55, 55, to press the plungers 44 yieldingly against the fabric strip overlying the plate 22 and to withdraw them therefrom.

10 To turn the shaft 50 in proper timed relation to cause the plungers 44 to move downward with the plate 22 while pressing the fabric against the plate, a lever 56 is secured upon the shaft 50 and is provided with a series 15 of attachment apertures 57, 57 for a cable 58 running from the turn-buckle 37, and for rotating the shaft 50 in the opposite direction to return the plungers 44 to their uppermost positions, after the retractive movement of 20 the presser assembly including the shaft 50. The shaft 50 has secured thereon an arm 59 which is connected by a pull spring 60 with the machine frame.

Just below the lowermost position of the 25 plate 22 a curved plate 61 is mounted in position to deflect the fabric strips so as to cause them to pass smoothly and in spread condition onto the set of endless belts 17.

In the operation of the device the plate 22 30 is in its uppermost position and receives the leading end of the fabric web on its forward face as the web is fed downward past the cutting line. In the forward movement of the presser bar 11 into engagement with the 35 fabric, to press the latter against the knife-guiding and fabric-backing members 14, 15, the shaft 50 is moved forward by reason of its connection, through the bars 54 and brackets 55, with the presser bar, which brings the 40 plungers 44 yieldingly into engagement at their outer ends with the fabric overlying the plate 22 so that the fabric to be severed from the web is gripped between the plate 22 and the plungers 44. As soon as the knife 45 13 has completed the cut, the cam 42 acts through the cable 36 to pull the plate 22 downward and also through the cable 58 to rotate the shaft 50 and thus swing the plung-

ers 44 downward with the outer ends moving at the same speed as the plate and pressing the fabric thereagainst, the downward movement of the plate 22 and plungers 44 thus forcibly dislodging the cut strip, breaking any adhesion that there may be between the strip and the residue of the web. As the plate 22 approaches its lowermost position, the retractive movement of the presser bar 11 and shaft 50 withdraws the plungers 44 from the fabric strip, permitting the latter to slide from the plate 22 and to be deflected by the 60 plate 61 onto the set of endless belts 17. The passage of the cam 42 from under the roller 41 then permits the spring 33 to return the plate 22 to its uppermost position and at the same time permits the spring 60 to rotate the shaft 50 counter-clockwise as viewed in Figs. 3 and 5 and thus to return the plungers 44 to their uppermost positions, this cycle of operations being repeated in the continuous operation of the machine.

70 Modifications are possible within the scope of my invention as defined in the appended claims.

I claim:

1. Sheet feeding means comprising a reciprocating gripper member adapted to engage one face of the sheet and mounted to slide therewith in the feeding movement and an oscillatory gripper member pivotally mounted to engage the opposite face of the sheet and to move therewith about its pivot in the feeding movement.

2. Sheet feeding apparatus as defined in claim 1 in which the oscillatory gripper member is mounted to slide, with relation to its pivot, from and toward the reciprocating gripper member.

3. Sheet feeding apparatus as defined in claim 1 in which yielding means is interposed between the oscillatory gripper member and its pivotal mounting to cause the said member to bear yieldingly against the sheet.

In witness whereof I have hereunto set my hand this 22nd day of September, 1927.

FRANK S. STERNAD.
